CLAIM

The ornamental design for a wearable weight, as shown and described.

DESCRIPTION

FIG. 1 is a front view of the wearable weight of a first embodiment of the new design, the rear view being a mirror image thereof;

FIG. 2 is a bottom view of the wearable weight of FIG. 1, the top view being a mirror image thereof;

FIG. 3 is a left side view of the wearable weight of FIG. 1, the right side view being a mirror image thereof;

FIG. 4 is an enlarged partial section view of the wearable weight taken along section line 4-4 of the endcap shown in FIG. 3;

FIG. 5 is a front view of the wearable weight of a second embodiment of the new design, the rear view being a mirror image thereof;

FIG. 6 is a bottom view of the wearable weight of FIG. 5, the top view being a mirror image thereof;

FIG. 7 is a left side view of the wearable weight of FIG. 5, the right side view being a mirror image thereof; and, FIG. 8 is an enlarged partial section view of the wearable weight taken along section line 8-8 of the endcap shown in FIG. 7.

The broken lines in the drawings illustrate portions of the wearable weight that form no part of the claimed design. The appearance of any portion of the wearable weight shown between the break lines forms no part of the claimed design.
